YARN PACKAGE HOLDER

James Joseph Kloran, Cumberland, Md., assignor
to Celanese Corporation of America, a corpora-
tion of Delaware

Application March 11, 1939, Serial No. 261,161

4 Claims. (Cl. 242—131)

This invention relates to textile apparatus employed for twisting and winding into package form materials such as yarn, thread, filaments, ribbon, straw and the like (all hereinafter referred to as yarn), and relates more particularly to an improved creel arrangement for such textile apparatus.

It is an important object of this invention to provide a novel creel arrangement whereby the time required for doffing and dressing is substantially reduced.

Another object of this invention is the provision of improved means for handling yarn packages, particularly yarn packages of large size, whereby contact of the yarn by the hands of the operatives is avoided thereby preventing broken filaments and soiled yarn.

Other objects and advantages of this invention, together with certain details of construction and combinations of parts, will appear from the following detailed description and claims.

In the drawing wherein the preferred embodiment of the invention is shown:

Figure 1 is a front elevational view of the improved creel arrangement, and

Figure 2 is a side elevational view, partly in section, of the same.

Like reference numerals indicate like parts throughout both views of the drawing.

Creels for twisting and winding apparatus, as heretofore commonly employed, consisted of standards mounted on the top of the machine and cross-bars, to which pins are fixed, attached to said standards. Since in this construction yarn packages are placed individually on the creel pins, they are therefore individually handled in changing from an empty package to a full one. The operatives in handling the yarn packages, particularly packages of large size, say on the order of 2 to almost 3 pounds, soil the yarn with their hands and even break the filaments thereof. In accordance with this invention means are provided for simultaneously handling a plurality of yarn packages, i. e. simultaneously doffing a plurality of yarn packages and simultaneously donning a plurality of replacements. By employing the construction of the present invention, handling of the individual yarn packages is reduced to a minimum and soiling of the yarn and breaking the filaments thereof is substantially obviated. Moreover, there results a substantial reduction in the time required for doffing.

Referring now to the drawing, the reference numeral 3 indicates a standard twisting and

winding machine to the top 4 of which are fixed standards 5, only one of which is shown. An arm or bracket 6 is mounted on each of the standards and is vertical adjustable thereon, being held in adjusted position by any suitable means as by a screw-bolt 7. The bracket is inclined somewhat away from the standard for a purpose hereinafter set forth. Angle irons 8 and 9 are fixed to the brackets 6, forming an open-bottomed trough or trough-like platform for the reception of a crate 11 containing a plurality of yarn packages 12.

The crate 11, which may be formed of wood or other suitable material, comprises end walls 13, side-pieces 14 and 15, and a bottom 16, all suitably joined together. The bottom 16 has fixed thereto pins 17, the number of which depends of course upon the number of yarn packages it is designed to hold. For ease of handling the crate, a bail or handle 18 is pivotally attached to the end walls 13. The bail may be so arranged as to act as a package retaining device to be slipped over the tops of the packages and in contact therewith.

In operation, the crate 11 containing a plurality of yarn packages, five of such yarn packages being shown in the drawing, is mounted in the trough formed by angle irons 8 and 9 on the brackets 6. The yarn 20 is drawn directly from packages 12 through pigtail guide 19 over rod 21 which is preferably chromium-plated. The pigtail guide 19 and the rod 17 are supported on an arm 22 adjustably mounted on standard 5. The inclination of the yarn packages, due to the construction of brackets 6, permits of the easy withdrawal of the yarn over the top of the package. The purpose of the bar 21 is to allow satisfactory clearance of the yarn past the crate on its way to pigtail guide 23 from which the yarn runs over an emulsion roll 24 and feed roll 25, through pigtail guide 26 and traveller 27 on to take-up bobbin 28. For the purpose of centering the crate 11, guide blocks 29 are fixed between angle irons 8 and 9.

When it is found desirable to doff the packages, the five packages are doffed simultaneously by lifting the crate from its position in the trough by means of handle 18. Another crate containing full packages of yarn is then set in the trough. By the device of the present invention, the time of change from empty to full packages is reduced substantially 30% and the former losses in spoiled yarn are substantially eliminated.

It is to be understood that the foregoing detailed description is given merely by way of illustration and that many variations may be made

therein without departing from the spirit of my invention.

Having described my invention, what I desire to secure by Letters Patent is:

1. An attachment for a textile machine having spaced standards, said attachment comprising brackets carried by said standards and spaced angle-irons mounted on said brackets forming a trough-like platform extending longitudinally across said textile machine, and a container within said platform, said container having spindles for supporting yarn packages, the construction and arrangement of said trough-like platform being such that the container may be readily and easily placed in position thereon and removed therefrom, and held against transverse movement while on said platform without the container being positively attached thereto.

2. An attachment for a textile machine having spaced standards, said attachment comprising brackets adjustably carried by said standards and spaced angle-irons mounted on said brackets forming a trough-like platform extending longitudinally across said textile machine, and a container within said platform, said container having spindles for supporting yarn packages, the construction and arrangement of said trough-like platform being such that the container may be readily and easily placed in position thereon and removed therefrom, and held against transverse movement while on said platform without the container being positively attached thereto.

3. An attachment for a textile machine having spaced standards, said attachment comprising

inclined brackets adjustably carried by said standards, spaced angle-irons mounted on said brackets forming a trough-like platform extending longitudinally across said textile machine, and a container within said platform, said container having spindles for supporting yarn packages, the construction and arrangement of said trough-like platform being such that the container may be readily and easily placed in position thereon and removed therefrom, and held against transverse movement while on said platform without the container being positively attached thereto, and means on said platform for preventing lengthwise movement of said container.

4. An attachment for a textile machine having spaced standards, said attachment comprising inclined brackets adjustably carried by said standards, spaced angle-irons mounted on said brackets forming a trough-like platform extending longitudinally across said textile machine, and a container within said platform, said container having spindles for supporting yarn packages, the construction and arrangement of said trough-like platform being such that the container may be readily and easily placed in position thereon and removed therefrom, and held against transverse movement while on said platform without the container being positively attached thereto, and blocks fixed to said platform for preventing lengthwise movement of said container.

JAMES JOSEPH KLORAN.
